UNITED STATES PATENT OFFICE.

ARCHIBALD DRYNAN, OF SEWICKLEY, PENNSYLVANIA.

WEATHER-STRIP.

SPECIFICATION forming part of Letters Patent No. 426,175, dated April 22, 1890.

Application filed December 31, 1889. Serial No. 335,505. (No model.)

To all whom it may concern:

Be it known that I, ARCHIBALD DRYNAN, a citizen of the United States, residing at Sewickley, in the county of Allegheny and State 5 of Pennsylvania, have invented certain new and useful Improvements in Weather-Strips; and I do hereby declare that the following is a full, clear, and exact description of the invention, which will enable others skilled in the 10 art to which it appertains to make and use the same, reference being had to the accompanying drawings, forming part of this specification.

The object of my invention is to provide a 15 simple, cheap, durable, and effective weather-strip which may be easily applied and removed and will be readily operated; and with this object in view the invention consists in a certain novel construction and combination 20 of devices, as fully described hereinafter in connection with the drawings, and specifically pointed out in the appended claims.

In the drawings, Figure 1 is a perspective view of the improved weather-strip applied 25 in the operative position to a door. Fig. 2 is a transverse sectional view of the bottom of the door and sill, showing the manner in which the strip closes the opening or crack therebetween. Fig. 3 is a detail view of the operating-lever and the door-knob to show the manner in which the former is fitted on the latter. Fig. 4 is a detail view of one end of the strip, 30 and Fig. 5 shows detail views of the plates which are secured to the door.

The strip A is provided at its ends near the upper edge with pintles *a a*, which are formed on plates B B', secured to the strip by screws or similar retaining devices. These pintles fit and operate in bearings or perforations in 40 the bearing-plates C C', which are secured to the inner surface of the door (which is shown at D) near its lower edge. The bearing-plate C is provided at its end with a perpendicular wing *c*, which contains the bearing *e*, whereby, 45 when the parts are in place, the body of the said plate C is arranged beneath and is concealed by the strip A. This plate C is obviously secured to the door (by means of suitable screws or the like) before the strip is put 50 in place, and it is preferably arranged near the free edge of the door, thereby giving a

neater appearance to that portion of the door which is more plainly visible. The plate C', however, is provided on its side edge near the lower end with a wing *c'*, similar to the wing 55 *c*, and provided, like the latter, with a bearing or perforation *e'*. This plate is applied to the door after the opposite end of the strip A is fitted to the bearing-plate C, the object in arranging the plate C' at right angles to 60 the plate C being obviously to enable its retaining-screws to be inserted. The plate C' being arranged near the hinged edge of the door is not easily seen, and therefore does not detract materially from the appearance of the 65 door.

The strip A carries near the end which is adjacent to the free edge of the door an outstanding arm or stud F, which may either be formed integral with the pintle-plate B, as shown in 70 the drawings, or may be independent thereof, said arm or stud being substantially perpendicular to the outer surface of the strip, and being provided at its free end with an eye *f* for the attachment of the lower end of the 75 operating wire or cord G.

The operating-lever H is affixed firmly to the knob of the door, whereby when said knob is turned to open the door the lever is moved, thereby drawing on the wire or cord and raising 80 the pivoted strip, whereby it may swing freely over the floor. This lever is provided at an intermediate point of its length with an outward offset *h*, in order to raise the free end of the lever from the surface of the lock, (or 85 door, in case a mortise lock is used.) The other end of the lever is provided with a square or angular opening I, which fits on the shank of the knob, and is thereby caused to move with the knob. To place the lever in 90 position, it is simply necessary to remove the knob which carries the barrel by loosening its retaining-screw, fit the squared opening of the lever on the exposed end of the knob-shank, and replace the said knob, properly tightening 95 its retaining-screw.

The lower edge of the strip A is rounded or chamfered, and a cushion or pad K is secured to the lower rounded or chamfered edge and passes up a short distance on the inner or 100 rear surface of the strip, whereby when the strip is in its operative position, as shown in

full lines in Fig. 2, it is substantially parallel with and in contact with the door, and the cushion or pad bears simultaneously against the surface of the door and against the floor 5 adjacent thereto, or, if a sill or carpet-strip is used, against the latter.

My improved strip is not intended to assume an inclined position, with its lower edge resting wholly on the floor, as I have found 10 that it is difficult to prevent the air from passing between the upper edge of the strip and the door; but, on the other hand, when in its operative position, the strip is nearly vertical, and the cushion or padding bearing simultaneously against the lower edge of the door 15 and against the floor or carpet strip. Thus the opening or crack between the door and floor or carpet strip is completely closed, thereby effectually excluding air and dust. 20 Another evident advantage of the improved weather-strip is that it requires no exclusive or independent manipulation. When the door-knob is turned in order to enable the door to be opened, the strip is raised by the 25 same operation, and when the knob is released on closing the door, the strip resumes its operative position without further attention. This simplification of the operation of the improved strip is of great advantage from 30 the fact that it cannot be injured or destroyed by carelessness or thoughtlessness. The same operation which is necessary to open the door operates the strip.

Having thus fully described my invention,

what I claim, and desire to secure by Letters 35 Patent of the United States, is—

1. The combination, with a strip provided at its ends with pintles, of the bearing-plate C, adapted to be secured to the door near its free edge and provided at its end with a perpendicular wing having a bearing to receive one of the pintles of the strip, the bearing-plate C', adapted to be secured to the door near its hinged edge and provided on its side edge with a wing having a bearing to receive the other pindle of the strip, and means to operate said strip, substantially as specified. 40

2. The combination, with a strip, of pintle-plates B B', secured thereto, the plate B being provided with an arm or stud F, the bearing-plates secured to the door and adapted to engage the pintles on said pintle-plates, said arm or stud having a seat or eye f, in which the operating lever or cord is secured, said cord or lever being attached at its other end 55 to a lever H, having an angular opening adapted to fit over the shank of the door-knob, and a pad K, secured to strip A, said pad lying between the door and strip A and under the edge of said strip, substantially as 60 described.

In testimony whereof I affix my signature in presence of two witnesses.

ARCHD. DRYNAN.
